UNITED STATES PATENT OFFICE.

CHARLES L. GOODRUM, OF URBANA, OHIO, ASSIGNOR, BY MESNE ASSIGNMENTS, TO
WESTERN ELECTRIC COMPANY, OF NEW YORK, N. Y., A CORPORATION OF ILLINOIS.

AUTOMATIC TELEPHONE-EXCHANGE.

1,161,655.

Specification of Letters Patent. Patented Nov. 23, 1915.

Application filed May 1, 1909. Serial No. 498,396.

To all whom it may concern:

Be it known that I, CHARLES L. GOODRUM, a citizen of the United States, residing at Urbana, in the county of Champaign and 5 State of Ohio, have invented certain new and useful Improvements in Automatic Telephone-Exchanges, of which the following is a specification.

My invention relates to improvements in 10 automatic telephone exchanges and the object of my invention is to provide means by which incoming calls are distributed over a series of switches less than the total number of lines and without the aid of distribution 15 switches, the constructions and arrangements being such that the switches shall be common to all the groups, so that if a switch relating to one group is busy the call would be passed on to the switch in another 20 group.

A further object of the invention is to so arrange the subscribers' circuits that the incoming calls shall be handled by the finder switch to which the group is normally assigned by the least possible movement thereof.

I accomplish these objects by the constructions and arrangements of parts hereinafter described and set forth in the claims.

30 In the accompanying drawings, Figure 1 is a view indicating the general arrangement of a section of the switchboard, such as would be used for five thousand subscribers. Fig. 2 is a diagrammatic view showing the 35 arrangement of the subscribers' circuits to the different finder switches, the arrangement being shown adapted to flat switches. Fig. 3 shows a similar arrangement of circuits and connections as applied to the two- 40 movement, or what is known as the up-and-around switch. Fig. 4 is a diagrammatic view showing the connections and circuits from the subscribers' stations to the finder switch and showing the arrangement of the 45 connections from one switch to another so that the incoming falls are distributed in the various switches, two switches only being indicated. Fig. 5 is a diagrammatic view showing the arrangement of the distribut- 50 ing or starting circuit. Fig. 6 is a diagrammatic view showing the operative circuit for continuing the operation of the switch after the same has been started over the starting circuit. Fig. 7 is a diagrammatic 55 view showing a modification.

Like parts are represented by similar characters of reference in the several views.

A general outline or general plan of my improved automatic telephone system is as follows: I employ the usual line and cut-off relays for each line, and I employ a certain number of finder switches less than the total number of subscribers' lines to which these subscribers' lines are connected in multiple. The proportionate number of 60 finder switches to the subscribers' lines may be varied at will and will be dependent upon the average number of calls originating in any particular group of subscribers.

In my illustrations I have used ten per 70 cent. as the basis for distribution or, in other words, for each fifty subscribers I use five finder switches and a corresponding number of selector switches and connector switches, it having been found, by experience, that in an ordinary exchange, say, from one to five thousand subscribers, ten 75 finder switches for each one hundred subscribers are sufficient to handle the incoming calls. It will be seen later, however, that 80 this number may be varied to suit any condition without in any way changing or modifying the system.

The subscribers' lines are arranged in 85 groups, each group preferably consisting of as many subscribers' lines as the total number of subscribers' lines divided by the number of switches assigned to said subscribers' lines. In other words, if the percentage of 90 switches employed is ten per cent. of the lines, then each group would preferably consist of ten lines. If the switches to be employed were to be 12½ per cent., then the group would preferably consist of eight 95 lines. If the number of switches were to be increased to 20 per cent., the groups could be decreased to five lines. In the illustration I have shown ten lines in each group. Each group of lines is connected in multiple 100 to the various switches assigned to that group. That is to say, on the basis of ten per cent., each group of ten lines out of the fifty lines would be preferably assigned to five switches. I also employ for each group of lines a starter wire which is primarily 105 connected to one of the switches, to which the lines of any group are connected and I arrange this starter wire so as to be extended to other switches of the group and to the switching relay thereof, so that when a call 110

is originated in any group and a finder switch is operated to find that line, the starter wire will be cut out of circuit with that switch, but extended successively to 5 such of the other switches as are in normal position.

In order to obtain the best results and provide for finding the line of a calling subscriber with the least effort and movement by the finder switch, I arrange the subscribers' groups so that, while each group is connected in multiple to each of the switches assigned to the total number of groups, incoming calls in either of said 10 groups will normally be assigned to one particular switch of the group of finder switches, but in the event that that particular finder switch is in use, then the call will be passed on to any other finder switch of 15 the group which is not in use. In making 20 this connection I preferably arrange the subscribers' circuits so that the first group, say, of ten lines, is assigned to the first ten contacts of the first switch, the second group 25 (of ten lines) is assigned to the first ten points or contacts of the second switch, a third group is assigned to the first set of contacts of the third switch and so on. The 30 multiple connections of these different groups are then connected to the different switches to succeeding series of contacts in different switches. That is to say, the ten lines coming into the first ten contacts of the first switch are connected to the second 35 ten in the second switch, the third ten in the third switch, the fourth ten in the fourth switch and the fifth ten in the fifth switch. The second group of ten is connected to the first ten in the second switch, the second ten 40 in the third switch, the third ten in the fourth switch, the fourth ten in the fifth switch and to the second ten in the first switch.

As shown in diagram in Fig. 2, the group 45 of lines coming into the first ten of the third switch would be connected to the second ten of the fourth switch, the third ten of the fifth switch, the third ten of the first switch and the fourth ten of the second switch and 50 the fifth ten of the third switch. It is obvious that if more than fifty lines are used, the multiple connections for the second, third, fourth and fifth switches of the group, instead of being carried back to the first, 55 second and so on, would be carried forward into another group, it being necessary only to double back or take the multiple connections back to the first switch from the last finder switch in the last group of finder 60 switches to the first switch of the first group of finder switches.

The finder switches and their arrangements, which I preferably use, are of the type which, when started by the closing of 65 the line relay on the subscriber's line, will

continue to operate by electric energy received from a local circuit, of which a terminal on the switching device is a part, (see Fig. 6) so that the switch operating mechanism receives an impulse from each 70 contact in the bank so long as the line relay of that particular subscriber is in its normal position, but which receives no current when the line relay has been operated by closing the subscriber's line. For the purpose of 75 this invention it is only necessary to show the method of starting the switching mechanism, as the starting of any switching device by the closing of any subscriber's line renders it inoperative for any other subscriber's line.

I will now proceed to describe the arrangements of the circuits and the operation of making a call from any group of subscribers' lines.

Fig. 1 will show the general arrangement of the line and cut-off relay, the finder switches, the first and second selector switches and the connector switches. As before stated, the finder switches are arranged in groups of five, the selector and connector switches are also preferably arranged in groups of fives. The line and cut-off relays are arranged in banks of fifty, that is, fifty relays correspond to five 95 switches. The subscribers' lines, as above stated, are, however, arranged in groups of tens, and the line and cut-off relays are also arranged in groups of tens, five groups in each bank.

Referring to Fig. 5, the line relays of any group of ten subscribers are adapted to close a circuit on the starting wire common to that group and in Fig. 5 I have shown the relays marked 1, 11, 21, 31 and 41 as representing the first line relay of each group, it being understood that there will be ten such relays in each group.

The finder switches relating to the fifty lines, represented by five groups of ten lines each, are marked a^1, a^2, a^3, a^4 and a^5 . Each of these switches, except the last one, a^5 , has been operated by the closing of the line relay of the group, so that the starter wire has been cut through or extended from each of the groups to switch, a^5 . This is accomplished as follows: Each of the switches, a^1, a^2, a^3, a^4 and a^5 , is provided with an auxiliary switch or circuit closer, b , which, when the switch is in normal position, is adapted to engage a contact, b^1 , and, when the switch is operated or is off-normal, to engage a contact, b^2 . There are three relays, c , d and e , associated with each switch, the relay, c , being the motor magnet which drives the switch from the impulses received from the line, d and e being one a quick and the other a slow relay, which are used in operating the switch and making the connections, as will be explained more fully hereinafter.

Upon the closing of any line in any group, say, from a subscriber's station A, a circuit will be closed through the line relay in the usual manner and as follows: From switch 5 hook A^1 , contact 2, wire 3, one winding of relay 1 (one) battery, other winding of relay 1, wire 4 back to hook A^1 . This operates the relay 1 (one) and closes the circuit from ground at 5, through contact 6, 10 circuit closer 7, line 8, circuit closer b , contact b^1 , line 9, contact 10, circuit closer 12, line 13, switch relay d , wire 14, battery 15, to ground at 16. This operates the switch relay, d , and closes the circuit from ground 17, contact 18, circuit closer 19, wire 20, motor magnet, c , wire 21, battery 15, to ground at 16, thus operating the motor magnet c . At the same time a circuit is closed from ground 17 (16 in Fig. 6), contact 18, circuit closer 20, wire 22, through relay e , wire 23, battery 15, and ground at 16. The closing of the circuit through the motor magnet, c , causes the switch, a^1 , to advance one step or to off-normal position, which closes the 25 switch or circuit closer, b , against the contact, b^2 , and open the circuit at b^1 . The relay, e , being a slow relay will not immediately be released and the motor magnet and relay, d , obtaining current through the line 30 contacts or banks of the switch, a^1 , will advance it until it finds the line operated, in the usual manner, after which the magnets, d , c and e , will be restored and the starter wire, 8, will be extended through circuit 35 closer, b , contact b^2 , line 24, contact 25, circuit closer 26, line 27, to switch or circuit closer lever b , on the finder switch a^2 , so that the subsequent operation of any line relay in that first group would close a circuit through the line 27, to the switch lever b , contact b^2 , wire 9, contact 10, circuit closing lever 12, wire 13, to relay d of the second switch a^2 , which, through the 40 circuits before described, would cause this switch to move one step or to off-normal position, thus allowing the lever, b , to engage with contact b^2 , and extend the starter line through line 24 and the relay contacts of the relay, e , relating to switch a^2 , to the 45 switch lever, b , of the third switch, and so on through the series.

As shown in Fig. 5, all the switches, except a^5 , have been started, hence a call originating in any line of any group will 50 be transferred to switch a^5 . If it should come in on switch a^5 , the closing of the line relay 41 would close the circuit from ground 5, as heretofore described, through circuit closing lever, b , contact b^1 , line 10, and circuit, heretofore described, to relay, d^5 , relay e^5 , and motor magnet c^5 , as heretofore 55 described. Whenever any switch is released the off-normal switch, b , is closed to the contact b^1 , for that switch, so that if a second call should originate in any group, say,

in the line group containing relay 41, the circuit would be closed from ground 5, contact 6, circuit closer 7, off-normal switch b , contact b^2 , line 24, contact 25, circuit breaker 26 and line 28 back to the off-normal switch, circuit, breaking lever b , of switch a^1 . If this switch has been operated the line will be extended, as heretofore described, through the contacts 25, 26 of relay e^1 , line 27, to contact b of switch a^2 , which, if in normal position, will be operated, if not, the call will be cut through, as before described, to the various other switches.

It will be understood that, associated with each line, is a line relay a and cut-off relay f , (see Fig. 4) which latter, so soon as the line is found by the finder switch, is operated to cut off the line relay and restore it to normal position in the usual way by wiper 33 engaging the contact 34 (corresponding to the line operated) thus placing ground on said contact and operating the cut off relay over the circuit from grounded wiper 33, contact 34, wires 35, 36, relay f , 90 battery and ground as shown in Fig. 4, the wiper 33 being grounded in the usual way. It will be understood that the starter wire 8 extends to a circuit closer 7, on each of the line relays, a , in a group. Fig. 4 also 95 illustrates the method of connecting the different lines in multiple to the different switches. For instance, the lines from the station, A^5 , are connected in multiple to switches, a^1 and a^2 . In Fig. 4 the lines 100 from this station are represented as terminals No. 5 on the switch, a^1 , and connected in multiple to terminals No. 15, on the second switch, a^2 . So also, station A^7 is connected to terminal 7 in the first finder switch, 105 a^1 , in the first group of ten, and to terminal 17 in the second group of ten in the second switch, a^2 .

In Figs. 2 and 3 I have shown how these multiple connections are made, Fig. 2 representing a flat switch. The lines of the first group of ten are brought into the first contacts, as indicated at g^1 , in switch a^1 . These same lines are connected in multiple to the second group of ten contacts in the 115 second switch, as shown at g^2 in switch a^2 , to the third group of ten in the third switch, as shown at g^3 on switch a^3 , the fourth group of ten in the fourth switch, as shown at g^4 on switch a^4 , and the fifth 120 switch in the fifth group, as shown at g^5 on switch a^5 . The next group of ten lines will be brought to the first ten contacts of switch a^2 , as shown at g^1 . These lines would appear on the second group of ten on the 125 switch a^3 , as shown at g^2 on switch a^3 , g^4 on switch a^5 , g^5 on switch a^1 . The next group would appear at g^1 on switch a^3 , g^2 on switch a^4 , g^3 on switch a^5 , g^4 on switch a^1 , and g^5 on switch a^2 . The succeeding groups of 130

lines would come into the first group of contacts on the succeeding switches and multiple to the other switches in the same way.

In the two-movement, or up-and-around, 5 switch the connections would be arranged in the same way, except that, instead of being arranged in groups around the bank, the groups would be placed in different levels, preferably five levels in each switch and ten 10 contacts in each level. In this case, the first group of ten would come into the contacts on the first level of switch a^1 , the second level of switch a^2 , the third level in switch a^3 , the fourth level in switch a^4 and the fifth level 15 in switch a^5 . The second group would come into the first level of switch a^2 , the second level of switch a^3 , the third level of switch a^4 , the fourth level of switch a^5 and the first level of switch a^1 . The next group would 20 come to the first level of switch a^3 , second level of switch a^4 , third level of switch a^5 , fourth level of switch a^1 and fifth level of 25 switch a^2 , and so on throughout the series.

It will be seen thus that the operation of 25 any line relay starts a switch to which that line relay is normally assigned. The starting of this switch will extend the starter wire to the next switch, so that any line relay operated in the first group will have 30 its call transferred to the second switch, but it will take the second group in this switch or, in case of the up-and-around switch, it will take the second level and so on.

Any call arising in a group, which is 35 normally assigned to a certain switch, will always come in on the first group of contacts in that particular switch, hence, in the normal working of the system, the first ten contacts of each switch are the ones that are 40 used, but, in the event that the switch is busy, such call would be transferred to the next switch, which switch would find its line in the second group. If this switch were also busy it would be extended to the 45 next switch and find its line in the third group and so on, so that, in the normal position, the switches are required to operate the least possible distance in finding the line and it is only in cases that the switches assigned to the lines are busy that the switches 50 will be required to move over more than ten points to make the contacts.

In the above description I have described the number of switches as corresponding 55 with the number of groups and, while this is the preferable arrangement, it is not necessary as it is obvious that one might have a larger number of groups with a smaller number of switches. For instance, ten 60 groups of ten lines each might be accommodated on five switches, in which case, two groups would be normally assigned to each switch with the means described for extending the calls into the next switch in case 65 that the particular switch is busy. So also

it is not necessary to make the multiple connections from the last switch to any particular group back to the first, as these multiple connections may be extended from one group of switches into another group of switches almost indefinitely, and multiple back only from the last switch in the last group to the first switch in the first group. 70

It is obvious that the number of switches employed depends on the number of calls originating in the groups and, if it were a system where only a few calls are likely to arise at the same time, the number of switches can be reduced, while the groups of subscribers could remain the same. This 75 is particularly true on the two-movement or up-and-around switch where the preferable and desirable number of subscribers in a group would be the number of contacts in a given level of which the desirable number 80 is found to be ten, so it might be found that, where there were fifty lines and the probability of not more than two calls originating at the same time, two switches might be arranged to handle the connections, although the number of lines might be divided into five groups, representing five levels on the switch, so that, while the groups of lines are here described as being the same as the number of switches in a group, it does not 85 necessarily follow that this should be always used. 90

It is also obvious that the number of switches might be considerably larger than the number of groups of subscribers in cases 95 where a large number of calls might originate simultaneously in a single group. For instance, ten switches might be assigned to 100 five groups. In this case, instead of making the groups smaller, the groups might remain the same and each group assigned normally to two switches and the multiple connections made to the switches in pairs instead of in units as shown in Fig. 7. The 105 advantage of the system being its flexibility and its adaptability to any requirement in the relation of calls to the number 110 of lines used.

Having thus described my invention, I 115 claim:

1. In an automatic telephone system, subscribers' circuits arranged in groups, finder switches each having a series of contacts arranged in groups and equal in number to the subscribers' circuits in several groups, 120 each group of subscribers' circuits being connected to the first group of contacts in one of said switches and in multiple to succeeding groups of contacts in different switches.

2. In an automatic telephone system, subscribers' circuits arranged in groups, a series of switches corresponding in number to the number of groups, each of said groups being connected to the first group of contacts in one of said switches and connected in mul- 125 130

5. In an automatic telephone system, a plurality to succeeding groups of contacts in different switches, a starter wire common to all the subscribers' circuits in one group and leading to a switch assigned to that group, and means for extending said starter wire to other or different switches when a switch to which it is normally extended has been operated. 70
6. In an automatic telephone system, subscribers' circuits arranged in groups, finder switches, each having a series of contacts arranged in groups, each group of contacts corresponding in number to the subscribers' circuits in a group, and each group of subscribers' circuits being connected to the first group of contacts in one of said switches and in multiple to succeeding groups of contacts in different switches, as specified. 75
7. In an automatic telephone system, subscribers' circuits arranged in groups, a series of switches each having contacts arranged in groups, each group corresponding in number to the number of subscribers' circuits in a group, each of said groups of circuits being connected to the first group of contacts in one of said switches and in multiple to succeeding groups of contacts in different switches, a starter wire common to all the subscribers' circuits in one group leading to a switch assigned to that group, and means for extending said starter wire to other or different switches when a switch to which it is normally extended has been operated. 80
8. The combination with a series of electric circuits arranged in groups, switches less in number than the lines to which said lines are connected in multiple, a starter wire for each group normally terminating in one of said switches, means for extending the starter wire to another switch when the first switch is operated and means in said starter wire extension for holding open said extension during the operation of the first switch. 85
9. The combination with a progressively movable switching mechanism, a series of lines arranged in groups and connected in multiple to different switches, a line relay in each line and a starter wire common to the lines of one group having branches to each line relay, an operating circuit for each group also having circuit branches to said relay, means for closing the starting branch and opening the operating branch when the relay is operated, and means for extending said starter wire to another switch when the first switch is operated. 90
10. In an automatic telephone system, subscribers' circuits arranged in groups, finder switches, each having a series of passive contacts arranged in similar groups and equal in number to the subscribers' circuits in the several groups, a preferred group of contacts for each group of subscribers' circuits, movable contacts one preferentially associated with each group of subscribers' circuits, and each contact associated with the other group of subscribers' circuits in an ascending sequence of preference. 95
11. In an automatic telephone system, subscribers' circuits arranged in groups, finder switches, each having a series of passive contacts arranged in groups and equal in number to the subscribers' circuits in the several groups, movable contacts, means providing for a determined order of preference between the various groups of stationary contacts and each movable contact, whereby the group of lines represented by 100
12. In an automatic telephone system, subscribers' circuits arranged in groups, finder switches, each having a series of passive contacts arranged in groups and equal in number to the subscribers' circuits in the several groups, movable contacts, means providing for a determined order of preference between the various groups of stationary contacts and each movable contact, whereby the group of lines represented by 105
13. In an automatic telephone system, subscribers' circuits arranged in groups, finder switches, each having a series of passive contacts arranged in groups and equal in number to the subscribers' circuits in the several groups, movable contacts, means providing for a determined order of preference between the various groups of stationary contacts and each movable contact, whereby the group of lines represented by 110
14. In an automatic telephone system, subscribers' circuits arranged in groups, finder switches, each having a series of passive contacts arranged in groups and equal in number to the subscribers' circuits in the several groups, movable contacts, means providing for a determined order of preference between the various groups of stationary contacts and each movable contact, whereby the group of lines represented by 115
15. In an automatic telephone system, subscribers' circuits arranged in groups, finder switches, each having a series of passive contacts arranged in groups and equal in number to the subscribers' circuits in the several groups, movable contacts, means providing for a determined order of preference between the various groups of stationary contacts and each movable contact, whereby the group of lines represented by 120
16. In an automatic telephone system, subscribers' circuits arranged in groups, finder switches, each having a series of passive contacts arranged in groups and equal in number to the subscribers' circuits in the several groups, movable contacts, means providing for a determined order of preference between the various groups of stationary contacts and each movable contact, whereby the group of lines represented by 125
17. In an automatic telephone system, subscribers' circuits arranged in groups, finder switches, each having a series of passive contacts arranged in groups and equal in number to the subscribers' circuits in the several groups, movable contacts, means providing for a determined order of preference between the various groups of stationary contacts and each movable contact, whereby the group of lines represented by 130

the first preferred group of contacts in each switch are given preference in an ascending numerical sequence in the remaining switches.

- 5 12. In an automatic telephone system, subscribers' circuits arranged in groups, finder switches each having a series of stationary contacts arranged in groups and equal in number to the subscribers' circuits
 10 in the several groups, movable contacts, means to establish a determined order of preference between the various groups of stationary contacts and each movable contact, whereby the preferred group of contacts of
 15 a particular switch will be given preference in an ascending numerical sequence in the remaining switches.
13. In an automatic telephone system, subscribers' circuits arranged in groups, a plurality of finder switches less in number than the number of subscribers' circuits, stationary contacts to which said circuits are multiplied and coöperating movable contacts, a preferred group of contacts in each switch adapted to be engaged by a minimum movement of the movable contacts of said switch and by progressively greater movements of the other switches, and means responsive to a call on any line to start a switch which can engage the stationary contacts of that line in the least movement provided that switch is idle, or if that switch is busy to start the switch which can engage the stationary contacts of that line in the next least movement, or if the second switch is busy to start the switch which can engage the stationary contacts of a line in the next least movement and so continue through the plurality of switches providing they are busy to the switch which requires the maximum movement to engage the stationary contacts of the line.
- 20
 25
 30

14. In an automatic telephone system, subscribers' circuits arranged in groups, a plurality of finder switches less in number than the number of subscribers' circuits, stationary contacts to which said circuits are multiplied and coöperating movable contacts, a preferred group of contacts in each switch adapted to be engaged by a minimum movement of the movable contacts of said switch and by progressively greater movements of the other switches, and means responsive to a call on any line to start a switch which can engage the stationary contacts of that line in the least movement provided that switch is idle, or if that switch is busy to start the switch which can engage the stationary contacts of that line in the next least movement, or if the second switch is busy to start the switch which can engage the stationary contacts of a line in the next least movement and so continue through the plurality of switches providing they are busy to the switch which requires the maximum movement to engage the stationary contacts of the line.

In testimony whereof, I have hereunto set my hand this 16th day of April, 1909.

CHARLES L. GOODRUM.
